RALPH M. MILLER, OF PEORIA, ILLINOIS, ASSIGNOR TO PEORIA DRILL & SEEDER COMPANY, OF PEORIA, ILLINOIS, A CORPORATION OF ILLINOIS.

SCRAPER FOR DISKS.

1,160,638.

Specification of Letters Patent.

Patented Nov. 16, 1915.

Application filed July 12, 1912. Serial No. 709,116.

To all whom it may concern:

Be it known that I, RALPH M. MILLER, a citizen of the United States, a resident of Peoria, in the county of Peoria and State of Illinois, have invented new and useful Improvements in Scrapers for Disks, of which the following is a specification.

My invention relates to disk seed drills and particularly to cleaning or scraping parts therefor.

When a disk seed drill is operated in wet weather or in heavy or sticky soil it has been found advisable and necessary to provide devices for scraping the surfaces of the disks near their peripheries to clean the disks of the mud or other material adhering thereto, so that the edges of the disks will not be prevented from entering the soil a proper distance for seeding. These scraping or cleaning devices usually consist of blades having sharpened edges which are yieldingly held against the surfaces of the disks at an angle thereto. Where a drill has been exposed to wet weather for some time or is used in heavy or sticky soil, the surfaces of the disks become rusty and a thin coating of dirt will collect on the disks, thereby lifting the scraper off the surface of the disks and allowing the disk to revolve without being cleaned. To prevent this it is desirable to reverse the scraper and use the other edge which, as the result of prior use, is sharper and will act efficiently to clean the disks from rust, dirt and other substances.

The object of my present invention is to provide a scraper which may be readily reversed and which in either position will be held at the same inclination to the disks and with the same pressure.

A further object of my invention is the provision of a simple locking and securing means which holds the scraper securely on its locking lever and prevents accidental displacement or disengagement.

To the accomplishment of the foregoing and such other objects as may hereinafter appear, my invention consists in the construction, combination and arrangement of parts hereinafter described and then sought to be defined in the appended claims, reference being had to the accompanying drawing forming a part hereof, which for the purpose of illustrative disclosure shows an embodiment of my invention, it being understood however that changes may be made in

practice within the scope of the claims without digressing from my inventive idea.

In the drawings: Figure 1 represents a side elevation of the seeder disk with my invention applied thereto. Fig. 2 is a perspective view of the scraper blade. Fig. 3 is a plan view of the scraper blade and the holding lever. Fig. 4 is a perspective view of one extremity of the holding lever, and Fig. 5 is a central longitudinal section thereof.

My invention generally comprises a holding lever which is pivotally mounted on the grain spout casting and has a spring pressure exerted at one end to yieldingly force the other end toward the disk. The other end of the lever is formed as one part of a two part connection for the scraper blade to which the other part of said connection is attached. The extremity of the holding lever is in the form of a bifurcated hook having a lug extending outwardly from the bifurcation to form an abutment. This hook forms a bearing and in it is adapted to rest the corresponding part of the connection which is secured to the scraper blade and which includes pintles which bear in the two hook portions of the holding lever and the bearing arms or members, the extremities of which are turned upwardly to provide stops to engage the abutment and properly position the scraper blade relative to said disks. The connecting part, which is attached to the scraper blade, is made reversible so that by removing it from its bearing in the end of the holding lever and reversing it, it will be secured therein in the same position relative to the disk, thereby assuring that the scraper blade will always operate in the same manner on the disks.

Referring now to the drawings for a particular description of my device, the numeral 1 designates the grain spout casting having the draw bar connection 2, and also the disk 3 mounted thereon, these parts all being of the usual and conventional construction. The casting 1 is further provided with the apertured lug 4, it being understood that this lug is duplicated on the side opposite to that shown. This casting also has the aperture 5 therethrough which permits the passage of the pressure spring 6 which bears against the ends 7 of the holding levers 8, encircling the studs 9 thereon. As the levers 8 are the same in construction and operation and are merely duplicated on 11c

opposite sides of this device it is only deemed necessary to describe and show one of them. Each lever is provided intermediate thereof with the extended stud 10 which has a bearing in the apertured lug 4, being held therein by the cotter pin 11. This provides the pivot for the holding lever whereby the lower extremity thereof may be moved to and from the disk during the operation of the device. A scraper member is adapted to be removably secured to said holding lever and to this end I provide the scraper blade 12 which is attached to the holding member 13, this member being so formed as to provide one part of the two part connection or coupling, the other part of said connection or coupling being formed by the end of the holding lever.

In the device illustrated, the lower extremity of the holding lever 8 is made in the form of a hook 14 which is bifurcated to provide the spaced extensions 15, having projecting outwardly therebetween the abutment 16 which has the square outer face 17 and the inner bearing face 17' at right angles thereto. This member 8 also has the upper hook extensions or prongs 18 which are spaced as at 19. A groove or depression 20' which forms a substantial extension of the spaces between the prongs of said hooks is formed in said member. This forms one member or part of the two part coupling, the other part being formed by the blade holding member. This blade member 13 is provided with oppositely disposed securing parts or portions 20 to which the blade is riveted or otherwise secured, the body portion 21 of the blade holder being positioned along the upper edge of the blade. Formed on and extending upwardly from this body portion is the member 22 which forms part of the connection or coupling. This member 22 is elongated in a direction transverse to the blade having the arms 23 with the flat bearing surfaces 23' terminating in the upturned projections or extensions 24, the inner surfaces 25 of which are substantially at right angles with regard to the surfaces 23'. Between said arms 23 is provided the rounded extension 26 which is reduced on its opposite sides to form the pintles or studs 27 leaving the shoulders 28.

In assembling the device the pintles bear in the spaced hook portions of the lower extremity of the lever with one arm 23 of the elongated member 22 fitting in the space between said hooks, the flat bearing surface 23' bearing against the flat surface 17' on the abutment 16 and thereby determining the inclination of the scraper relative to the lever and disk. The rounded extension 26 fits in the groove or depression 20' to assist in preventing relative lateral displacement.

The upward extension or projection 24 has its inner flat face 25 bearing against the

square end 17 of said abutment 16 to form a lock to hold the parts securely in engagement and prevent them disassembling. This is due to the action of the spring by forcing the lower end of the lever 8 inwardly until the scraper edge engages the disk. This interlocking relation of the pintles engaging in the hook and the upward extension or projection engaging the abutment, locks and holds the blade holding member in the end 75 of the lever at a predetermined inclination to the disk.

In order to remove the blade and its holder, it is necessary to swing the lower extremity of the lever outwardly away from the disk until the projection or extension 24 can clear the end of the abutment, thus breaking the locking relation, which normally exists due to the action of the spring forcing the inner end of the lever inwardly 85 so that the blade engages the disk and the extension or projection 24 engages the end of the abutment 16. The blade holding member is removed from engagement with the hook portion of the lever and reversed 90 and then replaced in position again. As the parts of the blade holding member are duplicated it fits in exactly the same manner as before and will be held and locked at the same angle and position relative to the disk. 95 The spring 6 normally tends to force the lower end of the lever inwardly, the scraping edge of the blade bearing against the disk as shown in Figs. 1 and 3. This being the case, the upturned extension or projection 24 bears on and is always held in tight engagement with the face 17 of abutment 16 as shown, so that the angular relation between the scraper and lever and the scraper and disk is always the same and the parts 100 locked securely together, the projection 24 and end of abutment 16 serving as a positive means for preventing accidental or unintentional displacement or disengagement of the parts.

It is obvious that by providing this simple form of connection or bearing between the holding lever and the blade that I have produced a device which operated efficiently and effectively to produce the result desired. The blade is capable of being readily reversed as the parts of the blade holding member are duplicated and not only that, but should one part be broken the other part may be used to form the connection with the lever.

What I claim is:—

1. A scraper for a disk, comprising a lever having a bifurcated hook portion at one end and an abutment at the termination of said bifurcation, a scraper member having a holding and positioning means, said means including pintles adapted to have a bearing in said hook and an extension or projection adapted to bear against said abutment. 130

2. A scraper for a disk, comprising a lever having a bifurcated hook portion at one end and an abutment at the termination of said bifurcation, a scraper member having a holding and positioning means, said means including pintles adapted to have a bearing in said bifurcated hook, arms adapted to be positioned in said bifurcation and projections or extensions adapted to engage said abutment.
3. A scraper for a disk, comprising a lever having at one end a bifurcated hook portion and an abutment at the extremity of said bifurcation, said abutment having a square outer end and a flat inner surface at right angles thereto, a scraper member provided with holding and positioning means, said means including pintles adapted to have a bearing in said bifurcated hook, arms adapted to be positioned in said bifurcation, the upper surface of said arms being flat and adapted to engage the flat inner surface of said abutment and the end of said arms being provided with upturned projections or extensions having flat inner surfaces adapted to engage the end of said abutment.
4. A scraper for a disk, comprising a lever having a bearing and an abutment formed at one end, a scraper member provided with reversible holding and positioning means, said means including pintles adapted to be positioned in said bearing and duplicate projections or extensions adapted to engage said abutment in either position so as to hold said scraper member at the same angle relative to said lever in either position.
5. A scraper for a disk, comprising a lever having a bearing and an abutment formed at one end, a scraper member provided with reversible holding and positioning means, said means including duplicate pintles adapted to rest in said bearing and duplicate arms extended at right angles to said pintles, each of said arms having an upturned extension or projection at its end adapted to engage said abutment.
6. A scraper for a disk, comprising a lever having a bifurcated hook portion at one end with an abutment at the termination of said bifurcation, a scraper member having reversible holding and positioning means, said means including duplicate pintles on opposite sides thereof adapted to rest in the bearing formed by said bifurcated hook, said means also having duplicate extended arms provided at their extreminal portions with upturned projections or extensions in the form of lugs to engage said abutment.
7. A scraper for a disk, comprising a lever having at one end an opening forming a bearing and an abutment, a scraping member, pintle members attached to said scraping member and adapted to have a reversible relation and bearing in the opening in said lever, and lugs also attached to the scraper and adapted to bear against said abutment.
8. A scraper for a disk, comprising a lever having at one end a hook portion formed with an opening extending transverse to the axis of the lever, which forms a bearing, said lever also having a slot or opening at right angles to said first mentioned opening, an abutment at the base of the slot or opening, a scraping member, means attached to said scraping member adapted to have a detachable and reversible bearing in the first mentioned opening in the lever, and a lug on said means adapted to enter the slot or opening in the lever and engage the abutment thereon.
9. A scraper for a disk, comprising a lever adapted to be pivotally mounted, a scraper, the lever provided at one end with an opening forming a bearing, the scraper provided with means adapted to be journaled in said bearing, a spring for yieldingly holding the lever in a position to cause the scraping edge to engage the face of a disk, and abutting portions on the scraper and lever for determining the angular relation between the scraper and lever the abutting portions of the scraper being duplicated on opposite sides thereof, whereby the position of the scraper may be reversed in the bearing.
10. A scraper for a disk, comprising a lever, adapted to be pivotally mounted and having at one end a bifurcated hook portion and an abutment at the termination of said bifurcation, a scraper member having a locking and positioning means, said means including pintles adapted to bear in said bifurcated hook, arms adapted to be positioned in said bifurcation, and projections or extensions on said arms adapted to engage and bear on the end of said abutment to lock the parts in position, and a spring for yieldingly holding the lever in a position to cause the scraper edge to engage the face of the disk and to hold said projections or extensions in engagement with said abutment.

In testimony whereof I affix my signature, in presence of two witnesses.
